Application October 9, 1951, Serial No. 250,495

Claims priority, application Germany
October 9, 1950

20 Claims. (Cl. 241—121)

1

The present invention relates to a grinding apparatus of the type in which grinding surfaces move with respect to each other to pulverize a material.

Conventional grinding machines of the above type have a grinding disc which engages a plurality of grinding rollers, the latter usually being hingedly mounted by means of pendulum-like supports, so that the rollers may give way with respect to the grinding disc when a particularly hard material is ground. The purpose of this yieldable mounting of the rollers is to prevent breaking of the machine parts.

This latter type of conventional construction has many defects because the pivotal mountings of the rollers must be well greased in order to be properly lubricated, and these pivotal mountings are generally inaccessibly located so that it is difficult to maintain the parts of the machine properly lubricated. Moreover it very frequently happens that dust arising from the material being ground enters into the bearings and causes the same to become worn after a very short time.

One of the objects of the present invention is to overcome all of the above defects.

Another object of the present invention is to provide a grinding machine with grinding parts which will need no lubrication.

An additional object of the present invention is to provide an extremely simple mounting and guiding means for the grinding rollers of a grinding machine.

A still further object of the present invention is to provide a grinding machine with a means for preventing dust from getting into bearings of the machine.

Yet another object of the present invention is to provide a grinding machine made of few, relatively simple, easily constructed parts, which are easy to maintain and freely accessible.

With the above objects in view, the present invention mainly consists of a grinding machine in which a grinding disc is mounted for rotation about an axis. This disc has on one side thereof an annular grinding face which is engaged by the peripheral grinding face of at least one grinding roller which has opposite side faces from which a pair of shaft portions extend. A spring means is operatively connected to the roller, through the medium of a stationary pressure ring, to urge the roller toward the disc in a direction substantially parallel to the axis of rotation of the latter. The contacting surfaces of the roller and pressure ring are made of hard

2

metal. The shaft portions extending from the roller are respectively located in slots respectively formed in a pair of ring members and extending in a direction substantially parallel to the axis of rotation of the disc, so that the roller is free to move in the direction of the slots. These ring members are rotatably mounted within the housing of the grinding machine. If desired, the shaft members of the grinding roller may be respectively located in bores of members connected to these ring members, and in this latter case the ring members are movable with the roller in a direction substantially parallel to the axis of rotation of the grinding disc. With this construction, a roller mounting which requires lubrication is entirely eliminated, and the hard metal at the contacting surfaces of the moving parts guarantees that these parts will give service for a long time before they will become appreciably worn.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a schematic, vertical, sectional view through one possible grinding machine constructed in accordance with the present invention;

Fig. 2 is a schematic, vertical, sectional fragmentary view of a somewhat different embodiment of a grinding machine constructed in accordance with the present invention; and

Fig. 3 is a partly sectional plan view of a construction similar to that of Fig. 2, showing a slightly different embodiment from that illustrated in Fig. 2.

Referring now to the drawings, there is shown in Fig. 1 a grinding machine having a cylindrical housing portion 1 which is flanged at its upper edge where it is connected to the flanged lower edge of a conical cover 3 of the grinding machine. The cylindrical housing portion 1 is supported at its lower flanged edge on the frame portion 2 of the grinding machine. In this frame portion 2 there is located a driving member 6 which is rotated by a driving mechanism not shown. From the member 6 there extends a stud 5 fixedly connected to the member 6 for rotation therewith and engaging a recess in the bottom of the grinding disc 4 so as to cause the

latter to rotate with the member 6. For example, the stud 5 and the mating recess of disc 4 may be of a non-circular cross-section so that they are constrained to rotate together. Supported on the frame portion 2 is a ring member 8, of a U-shaped cross-section, which has an annular projection on its upper surface located in an annular groove formed in a lower annular surface portion of the disc 4, so that the interior of the housing 1, in which the disc 4 is mounted for rotation about a vertical axis, is sealed off from the frame portion 2 by this ring member 8. A ring member 9 is fixedly mounted within the housing portion 1, by means of the bar members 10, and is located closely about the disc 4 so as to form an annular bearing for the latter.

The disc 4 is provided on its upper surface with an annular shoulder portion 11 upon which a grinding ring 12 having a grinding surface 14 is located. The ring 12 is prevented from rotation with respect to the disc 4 by the leaf spring members 13 located in opposite grooves formed in the engaging surfaces of annular portion 11 and ring member 12. If desired, the annular grinding portion may be formed integrally with the disc 4, as shown in Fig. 2.

A plurality of grinding rollers 15 having their axes inclined to the axis of rotation of disc 4 are located within the housing 1 and have their peripheral grinding face portion 16 engaging the annular grinding face 14, as illustrated. These grinding rollers 15 have opposite side faces from which shaft portions 17 and 18 respectively extend, these shaft portions being fixedly connected to the rollers 15. The shaft portions 17 and 18 are respectively located in slots 19 and 20 which extend in a direction parallel to the axis of rotation of disc 4 and are respectively formed in a pair of annular ring members 21 and 22 which are located concentrically with respect to each other about the axis of rotation of disc 4.

As is illustrated in Fig. 1, these ring members 21 and 22 may conveniently take the form of annular I-beams and are fixedly connected to each other by bar members 23, which may also be I-beams and which are inclined due to the fact that the ring member 22 is located nearer to the disc 4 than the ring member 21. Fixedly mounted on the upper surface of ring member 21 is an annular angle bar 24 which is mounted for rotation on a plurality of roller members 31, which are themselves mounted for rotation on the inner surface of the housing portion 1, as is shown in Fig. 1. The lower surfaces of the ring member 21 engages a plurality of rollers 31' similar to rollers 31 and also mounted on the interior of housing portion 1.

The rollers 15 are formed with a profiled, annular, hard metal surface which engages the lower, profiled, mating, hard metal surface of the pressure ring 26, which is stationary during the operation of the grinding machine. A plurality of bar members 27 are fixedly mounted on the interior surface of the housing portion 1 and extend toward the pressure ring 26, these members 27 each having an inner end portion located between a pair of members fixedly mounted on the annular outer side face of ring member 26 and located closely adjacent to the inner end portion of member 27 so that the pressure ring 26 is mounted only for vertical movement in the housing portion 1 in a direction substantially parallel to the axis of rotation of disc 4. The lower surface of ring 26 forms a track for rollers 15.

A ring member 25 is slidably mounted within the housing portion 1 for movement in a direction substantially parallel to the axis of rotation of disc 4 and may be adjustably located at a desired position with respect to pressure ring 26 by any suitable means such as, for example, the set screw members 25' threadedly mounted in threaded openings formed in the housing portion 1 and engaging the outer periphery of the ring 25.

Located between the pressure ring 26 and adjustable ring 25 are the springs 28 which urge the pressure ring 26 and the rollers 15 toward the grinding disc 4 with a pressure which may be regulated by adjustment of ring 25.

A conduit 29 leads through the wall of housing portion 3 to the interior thereof. On the inside of housing portion 3 the conduit 9 leads onto a chute 30 which is pivotally supported from the hinge pin 39 located in the housing portion 3. This chute 30 rests on an inner, annular, inclined surface portion of ring 25 so that material to be ground may be supplied to the grinding surface through elements 29 and 30.

A conduit 40 leads through the frame portion 2 to the interior of housing portion 1 by a path located about the ring member 9. This conduit 40 serves to supply air to the interior of housing portion 1.

A grinding machine of the above type may be used, for example, to pulverize coal so as to provide a combustible powder for the burners of a furnace, for example, and in this latter event the cover portion 3 will be connected by any suitable conduit means (not shown) to such burners, a sieve, for example, being located in such a conduit means to prevent relatively large pieces of fuel from being carried to the burners, these relatively large pieces of fuel falling back to the grinding machine to be further pulverized thereby.

The above described grinding machine operates as follows:

The drive means rotates member 6 which causes the disc 4 to rotate therewith, this disc 4 rotating the rollers 15 by contact therewith both about their own axes and about the axis of rotation of disc 4, the rollers 15 rolling with respect to the pressure ring 26. Material to be ground is fed to the rollers and grinding disc through elements 29 and 30, and air supplied through conduit 40 rises upwardly through the housing portion 1 to carry dust produced by the pulverizing action of the grinding machine to a burner, as described above. If extremely hard pieces of material are fed to the grinding machine, the rollers 15, due to the mounting of the shaft portions 17 and 18 in the slots 19 and 20, respectively, are free to move in a direction substantially parallel to the axis of rotation of disc 4, and the pressure ring 26 is free to move therewith in substantially the same direction. The ring members 21 and 22 rotate on the rollers 31 and 31' about the axis of rotation of disc 4 with the rollers 15.

The embodiment of the invention which is illustrated in Fig. 2 has substantially the same parts as the embodiment illustrated in Fig. 1 and accomplishes the same results. The essential difference between the embodiments of Figs. 1 and 2 is that the embodiment of Fig. 2 does not include roller members 31 and 31' to support the ring members 21 and 22 for rotation in the housing portion 1. Instead, in the embodiment of Fig. 2 the disc 4 is mounted on a central shaft member 35 which has an extension 34 extending

upwardly into the housing portion 1, this extension 34 carrying on its upper end a spherically shaped member 33. Located about the extension 34 of shaft 35 is a cap means 32 which includes an upper closure member 36 formed with a concave inner face which engages the spherical member 33. The inner ring member 22 is fixedly connected to the bottom edge of the cap means 32 so as to be supported thereby, and ring member 22 is rigidly connected to the outer ring member 21 by the bar members 23 which have flanged opposite ends respectively connected to the ring members 21 and 22. A bearing member 41 is mounted within the ring member 22 to engage the extension 34 of shaft 35 so as to prevent tilting of the cap means 32 about the extension 34 of shaft member 35.

On the outer surface of ring member 22 there are fixedly mounted a pair of plate members which extend in a direction parallel to shaft 35 and are located on opposite sides of shaft portion 18 extending from roller 15. On the inner surface of ring 21 there are also a fixedly mounted pair of plate members extending in a direction parallel to shaft 35 and located on opposite sides of shaft 17. Extending between and being fixedly connected to each of these pairs of plate members is a cross-plate member 17' which is formed with a bore through which one of the shaft portions 17, 18 extends these shaft portions having fixedly mounted thereon the collar members 37 and 38, respectively, which engage the cross-plate members to limit movement of the rollers in the direction of the shaft portions extending from the opposite sides thereof, respectively. The shaft 35 and its extension 34 is formed with a bore 42 which opens at 43 into the interior of the cap means 32.

The above-described construction operates in substantially the same manner as the embodiment of Fig. 1 except that the ring members 21 and 22 are movable along with the rollers 15 and pressure ring 26 in a direction parallel to the axis of rotation of disc 4, these ring members being mounted about extension 34 of shaft 35 for rotation with respect thereto. Air pressure is supplied to the interior of cap means 32 by way of the bore 42, 43 so as to prevent dust from entering the interior of the cap means 32, and the bearings within cap means 32 are thereby kept free of any dust.

Fig. 3 is a plan view of a grinding apparatus substantially the same as that of Fig. 2, the only difference being that the above-described cross-plate members 17' are omitted and each shaft portion extending from the rollers 15 is simply guided between a pair of plate members fixedly mounted on one of the ring members and located on opposite sides of the shaft portion, as described above. In the embodiment of Fig. 1 there are three rollers spaced at 120° from each other as illustrated in Fig. 3.

It will be understood that each of the elements described above, or two or more together, may also find a useful application in other types of grinding apparatus differing from the types described above.

While the invention has been illustrated and described as embodied in grinding apparatus having a grinding roller mounting which requires no lubrication, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A grinding machine, comprising in combination, a housing; a grinding disc mounted in said housing for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; and guiding means operatively connected to said shaft portions to guide said roller for free movement in a direction substantially parallel to said axis, said guiding means comprising a pair of ring members located concentrically about said axis and each having a pair of plate members fixedly mounted thereon, extending in a direction substantially parallel to said central axis and respectively located on opposite sides of one of said shaft portions.

2. A grinding machine, comprising in combination, a housing; a grinding disc mounted in said housing for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; and guiding means operatively connected to said shaft portions to guide said roller for free movement in a direction substantially parallel to said axis, said guiding means comprising a pair of ring members located concentrically about said axis, being mounted in said housing for movement in a direction substantially parallel to said axis and each having a pair of plate members fixedly mounted thereon, extending in a direction substantially parallel to said central axis and respectively located on opposite sides of one of said shaft portions, and a cross-plate member fixedly mounted on and extending between said pair of plate members and being formed with a bore through which one of said shaft portions extends.

3. A grinding machine, comprising in combination, a housing having a side wall provided with an inner cylindrical surface located about a central axis of said housing; bearing means mounted on said inner surface; a grinding disc mounted in said housing for rotation about said axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring

means operatively connected to said roller for urging the same against said disc in a direction substantially parallel to said axis; and guiding means operatively connected to said shaft portions to guide said roller for free movement in a direction substantially parallel to said axis, said guiding means comprising outer and inner ring members fixedly connected to each other, located concentrically about said axis and each being formed with a slot extending in a direction substantially parallel to said axis and being located about one of said shaft portions, said outer ring member being mounted on said bearing means for rotation about said axis.

4. A grinding machine, comprising in combination, a housing; a grinding disc mounted on a central shaft member in said housing for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; and guiding means operatively connected to said shaft portions to guide said roller for free movement in a direction substantially parallel to said axis, said guiding means comprising outer and inner ring members fixedly connected to each other, located concentrically about said axis and each having a pair of plate members fixedly mounted thereon, extending in a direction substantially parallel to said central axis and respectively located on opposite sides of one of said shaft portions, said inner ring member being supported on said central shaft member for rotation with respect thereto.

5. A grinding machine, comprising in combination, a housing; a grinding disc mounted on a central shaft member in said housing for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; and guiding means operatively connected to said shaft portions to guide said roller for free movement in a direction substantially parallel to said axis, said guiding means comprising outer and inner ring members fixedly connected to each other, located concentrically about said axis, being mounted in said housing for movement in a direction substantially parallel to said axis and each having a pair of plate members fixedly mounted thereon, extending in a direction substantially parallel to said central axis and respectively located on opposite sides of one of said shaft portions, and a crossplate member fixedly mounted on and extending between said pair of plate members and being formed with a bore through which one of said shaft portions extends, said inner ring member being supported on said central shaft member for rotation with respect thereto.

6. A grinding machine, comprising in combination, a housing; a grinding disc mounted in said housing, on a central shaft member having

an outer end, for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; and guiding means operatively connected to said shaft portions to guide said roller for free movement in a direction substantially parallel to said axis, said guiding means comprising outer and inner members fixedly connected to each other, located concentrically about said axis and each having a pair of plate members fixedly mounted thereon, extending in a direction substantially parallel to said central axis and respectively located on opposite sides of one of said shaft portions; and cap means mounted on said outer end of and being located about said central shaft member for rotation with respect thereto and being fixedly connected to said inner ring member to support the latter for rotation therewith.

7. A grinding machine, comprising in combination, a housing; a grinding disc mounted in said housing, on a central shaft member having an outer end, for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; guiding means operatively connected to said shaft portions to guide said roller for free movement in a direction substantially parallel to said axis, said guiding means comprising outer and inner ring members fixedly connected to each other, located concentrically about said axis and each having a pair of plate members fixedly mounted thereon, extending in a direction substantially parallel to said central axis and respectively located on opposite sides of one of said shaft portions; cap means mounted on said outer end of and being located about said central shaft member for rotation with respect thereto and being fixedly connected to said inner ring member to support the latter for rotation therewith; and fluid pressure means communicating with the interior of said cap means to prevent foreign matter from entering the same.

8. A grinding machine, comprising in combination, a housing; a grinding disc mounted in said housing, on a central shaft member having an outer end, for rotation about an axis, said grinding disc having an annular grinding face portion on one side thereof; at least one grinding roller having a peripheral grinding face located against said grinding face portion of said disc and having opposite side faces; a pair of shaft portions respectively extending from said opposite side faces of said roller; spring means operatively connected to said roller for urging the same against said disc in a direction substantially parallel to said axis; guiding means operatively connected to said shaft portions to guide said roller for free movement in a direction substantially parallel to said axis, said guiding means comprising outer and inner ring members fixedly

connected to each other, located concentrically about said axis and each having a pair of plate members fixedly mounted thereon, extending in a direction substantially parallel to said central axis and respectively located on opposite sides of one of said shaft portions; cap means mounted on said outer end of and being located about said central shaft member for rotation with respect thereto and being fixedly connected to said inner ring member to support the latter for rotation therewith; and bearing means located between said cap means and central shaft member to prevent tilting of said cap means with respect to said shaft member.

9. A grinding machine, comprising in combination, a housing; a grinding disc mounted in said housing for rotation about an axis, said grinding disc having an annular grinding face portion on one side thereof; at least one grinding roller having a peripheral grinding face located against said grinding face portion of said disc and having opposite side faces and an annular surface portion located adjacent said peripheral grinding face and one of said side faces; a pair of shaft portions respectively extending from said opposite side faces of said roller; a pressure ring located about said axis and having a surface portion engaging said annular surface portion of said roller, said pressure ring being mounted in said housing only for movement in a direction substantially parallel to said axis; spring means operatively connected to said pressure ring for urging the same against said roller in a direction substantially parallel to said axis; and guiding means operatively connected to said shaft portions to guide said roller for free movement with said pressure ring in a direction substantially parallel to said axis.

10. A grinding machine, comprising in combination, a housing; a grinding disc mounted in said housing for rotation about an axis, said grinding disc having an annular grinding face portion on one side thereof; at least one grinding roller having a peripheral grinding face located against said grinding face portion of said disc and having opposite side faces and an annular surface portion of hard metal located adjacent one of said side faces; a pair of shaft portions respectively extending from said opposite side faces of said roller; a pressure ring located about said axis and having a hard metal surface portion engaging said annular surface portion of said roller, said pressure ring being mounted in said housing only for movement in a direction substantially parallel to said axis; spring means operatively connected to said pressure ring for urging the same against said roller in a direction substantially parallel to said axis; and guiding means operatively connected to said shaft portions to guide said roller for free movement with said pressure ring in a direction substantially parallel to said axis, said guiding means comprising a pair of ring members located concentrically about said axis and each being formed with a slot extending in a direction substantially parallel to said axis and being located about one of said shaft portions.

11. A grinding machine, comprising in combination, a housing; a grinding disc mounted in said housing for rotation about an axis, said grinding disc having an annular grinding face portion on one side thereof; at least one grinding roller having a peripheral grinding face located against said grinding face portion of said disc and having opposite side faces and an annular

surface portion of hard metal located adjacent one of said side faces; a pair of shaft portions respectively extending from said opposite side faces of said roller; a pressure ring located about said axis and having a hard metal surface portion engaging said annular surface portion of said roller, said pressure ring being mounted in said housing only for movement in a direction substantially parallel to said axis; spring means operatively connected to said pressure ring for urging the same against said roller in a direction substantially parallel to said axis; and guiding means operatively connected to said shaft portions to guide said roller for free movement with said pressure ring in a direction substantially parallel to said axis, said guiding means comprising a pair of ring members located concentrically about said axis and each having a pair of plate members fixedly mounted thereon, extending in a direction substantially parallel to said central axis and respectively located on opposite sides of one of said shaft portions.

12. A grinding machine, comprising in combination, a housing; a grinding disc mounted in said housing, on a central shaft member for rotation about an axis, said grinding disc having an annular grinding face portion on one side thereof; at least one grinding roller having a peripheral grinding face located against said grinding face portion of said disc and having opposite side faces and an annular surface portion of hard metal located adjacent one of said side faces; a pair of shaft portions respectively extending from said opposite side faces of said roller; a pressure ring located about said axis and having a hard metal surface portion engaging said annular surface portion of said roller, said pressure ring being mounted in said housing only for movement in a direction substantially parallel to said axis; spring means operatively connected to said pressure ring for urging the same against said roller in a direction substantially parallel to said axis; and guiding means operatively connected to said shaft portions to guide said roller for free movement with said pressure ring in a direction substantially parallel to said axis, said guiding means comprising outer and inner ring members fixedly connected to each other, located concentrically about said axis and each having a pair of plate members fixedly mounted thereon, extending in a direction substantially parallel to said central axis and respectively located on opposite sides of one of said shaft portions; cap means mounted on said outer end of and being located about said central shaft member for rotation with respect thereto and being fixedly connected to said inner ring member to support the latter for rotation therewith; and fluid pressure means communicating with the interior of said cap means to prevent foreign matter from entering the same.

13. A grinding machine, comprising in combination, a housing; a grinding disc mounted in said housing, on a central shaft member for rotation about an axis, said grinding disc having an annular grinding face portion on one side thereof; at least one grinding roller having a peripheral grinding face located against said grinding face portion of said disc and having opposite side faces and an annular surface portion of hard metal located adjacent one of said side faces; a pair of shaft portions respectively extending from said opposite side faces of said roller; a pressure ring located about said axis and having a hard metal surface portion engaging said annular surface portion of said roller, said pressure ring being

11

mounted in said housing only for movement in a direction substantially parallel to said axis; spring means operatively connected to said pressure ring for urging the same against said roller in a direction substantially parallel to said axis; guiding means operatively connected to said shaft portions to guide said roller for free movement with said pressure ring in a direction substantially parallel to said axis, said guiding means comprising outer and inner ring members fixedly connected to each other, located concentrically about said axis and each having a pair of plate members fixedly mounted thereon, extending in a direction substantially parallel to said central axis and respectively located on opposite sides of one of said shaft portions; cap means mounted on said outer end of and being located about said central shaft member for rotation with respect thereto and being fixedly connected to said inner ring member to support the latter for rotation therewith; fluid pressure means communicating with the interior of said cap means to prevent foreign matter from entering the same; and bearing means located between said cap means and central shaft member to prevent tilting of said cap means with respect to said shaft member.

14. A grinding machine comprising, in combination, a housing; a grinding disc turnably mounted in said housing for rotation about a vertical axis, and said grinding disc having a top face provided with an annular grinding surface; a plurality of grinding rollers located in spaced relation to each other over said grinding disc and each having a peripheral grinding face engaging said grinding surface of said grinding disc, said rollers each being mounted in said housing for rotation about an axis inclined to said vertical axis and extending downwardly toward the same, and each of said rollers being formed adjacent said peripheral grinding face thereof with an annular, substantially V-shaped groove; an annular pressure ring located in said housing about said vertical axis and having an annular substantially V-shaped underside mating with and engaging said grooves of each roller on the side thereof distant from said grinding disc, said pressure ring being mounted in said housing for free movement in a vertical direction; and spring means engaging said pressure ring on the top side thereof and urging the same downwardly toward said grinding disc so that each of said rollers are turnable about said inclined axis while being yieldably movable in a vertical direction away from said grinding disc.

15. A grinding machine comprising, in combination, a housing; a grinding disc turnably mounted in said housing for rotation about a vertical axis, and said grinding disc having a top face provided with an annular grinding surface; a plurality of grinding rollers located in spaced relation to each other over said grinding disc and each having a peripheral grinding face engaging said grinding surface of said grinding disc, said rollers each being mounted in said housing for rotation about an axis inclined to said vertical axis and extending downwardly toward the same, and each of said rollers being formed adjacent said peripheral grinding face thereof with an annular, substantially V-shaped groove of a smaller diameter than said peripheral face thereof; an annular pressure ring located in said housing about said vertical axis and having an annular substantially V-shaped underside mating with and engaging said grooves of each roller on the side thereof distant from said grinding disc, said

5 pressure ring being mounted in said housing for free movement in a vertical direction; and spring means engaging said pressure ring on the top side thereof and urging the same downwardly toward said grinding disc so that each of said rollers are turnable about said inclined axis while being yieldably movable in a direction vertically away from said grinding disc.

16. A grinding machine comprising, in combination, a housing; a grinding disc turnably mounted in said housing for rotation about a vertical axis, and said grinding disc having a top face provided with an annular grinding surface; a plurality of grinding rollers located in spaced relation to each other over said grinding disc and each having a peripheral grinding face engaging said grinding surface of said grinding disc, said rollers each being mounted in said housing for rotation about an axis inclined to said vertical axis and extending downwardly toward the same; an annular pressure ring located in said housing about said vertical axis and having an underside engaging each pressure roller on the side thereof distant from said grinding disc, said pressure ring being mounted in said housing for free movement in a vertical direction; spring means engaging said pressure ring on the top side thereof and urging the same downwardly toward said grinding disc so that each of said rollers are turnable about said inclined axis while being yieldably movable in a vertical direction away from said grinding disc; a pair of shafts fixed to each of said rollers and respectively extending from opposite sides thereof along said inclined axis; and an annular guide means turnably mounted in said housing for rotation about said vertical axis and having portions located on opposite sides on each of said shafts to guide the latter for vertical movement.

17. A pulverizing mill comprising a circular pressure ring, at least one wear-resistant running surface on said pressure ring, springs for exerting pressure on, and resiliently controlling the vertical movement of, said ring, a rotatably mounted grinding track axially disposed with respect to said pressure ring, means for rotating the grinding track, a plurality of grinding rolls interposed between the pressure ring and the grinding track, at least one spacing element for maintaining said grinding rolls in fixed relative axial positions, and substantially horizontal extensions on said grinding rolls for transmitting the spring pressure from said pressure ring, through the rolls to said grinding track, said extensions being of smaller diameters than the rolls and arranged axially to protrude from said grinding rolls and being adapted to roll directly against the wear-resistant surface of the pressure ring and in permanent clearance from the grinding track.

18. A grinding machine comprising, in combination, support means; a grinding disc turnably mounted on said support means for rotation about a predetermined axis, said grinding disc being provided with an annular grinding surface; a plurality of grinding rollers located in spaced relation to each other and each having a peripheral grinding face engaging said grinding surface of said grinding disc, said rollers each being mounted for rotation about an axis intersecting said predetermined axis and each of said rollers having adjacent said peripheral grinding face thereof an annular surface coaxial with said peripheral grinding face and being of a different diameter than said peripheral grinding face; and track means non-rotatably mounted by said support

means and frictionally engaging said annular surfaces of said grinding rollers, whereby during rotation of said grinding disc said grinding rollers turn in translation about said predetermined axis.

19. A grinding machine comprising, in combination, support means; a grinding disc turnably mounted on said support means for rotation about a predetermined axis, said grinding disc having an annular grinding surface; a plurality of grinding rollers located in spaced relation to each other and each having a peripheral grinding face engaging said grinding surface of said grinding disc, said rollers each being mounted for rotation about an axis inclined to said predetermined axis and extending toward said grinding disc, and each of said rollers being formed adjacent said peripheral grinding face thereof with an annular surface coaxial with said peripheral grinding face and being of a smaller diameter than the same; an annular pressure ring non-rotatably held by said support means and frictionally engaging said annular surfaces of said grinding rollers, whereby during rotation of said grinding disc said grinding rollers turn in translation about said predetermined axis.

20. A grinding machine comprising, in combination, support means; a grinding disc turnably mounted on said support means for rotation about a predetermined axis, said grinding disc having an annular grinding surface; an annular pressure ring non-rotatably held by said support means, being located about said axis, and being located opposite and facing said grinding disc; a plurality of grinding rollers located in spaced relation to each other between said grinding disc and pressure ring and each having a peripheral grinding

face engaging said grinding surface of said grinding disc, said rollers each being mounted for rotation about an axis inclined to said predetermined axis and extending toward said grinding disc, and each of said rollers being formed outwardly of said peripheral grinding face thereof with an annular surface coaxial with said peripheral grinding face, being of a smaller diameter than the same, and frictionally engaging said annular pressure ring; and spring means engaging said pressure ring for urging the same toward said grinding disc, whereby during rotation of said grinding disc said grinding rollers turn in translation about said predetermined axis.
